US0D1068872S

(12) **United States Design Patent** (10) **Patent No.:** **US D1,068,872 S**
(45) **Date of Patent:** **** Apr. 1, 2025**

(54) **3D PRINTER**

(71) Applicant: **Stratasys, Inc.**, Eden Prairie, MN (US)

(72) Inventors: **Jeff Lee Chapman**, New Prague, MN (US); **James Flannigan**, Roseville, MN (US); **Patrick Anderson**, Maple Grove, MN (US); **Dang Yang**, Champlin, MN (US); **Christopher Herbst**, St. Louis Park, MN (US); **Brett Johnson**, Roseville, MN (US); **Colin Schiel**, Chaska, MN (US)

(73) Assignee: **STRATASYS, INC.**, Eden Prairie, MN (US)

(**) Term: **15 Years**

(21) Appl. No.: **29/845,433**

(22) Filed: **Jul. 7, 2022**

(51) **LOC (15) Cl.** **15-09**

(52) **U.S. Cl.**

USPC **D15/122**

(58) **Field of Classification Search**

USPC D15/122, 135–136, 138, 141, 199;
D18/6–7

(57) **CLAIM**

The ornamental design for a 3D printer as shown and described.

DESCRIPTION

FIG. 1 is a perspective view of a 3D printer showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a second perspective view thereof.

The broken lines shown in the drawings are included for purposes of illustrating portions of the 3D printer and form no part of the claimed design.

1 Claim, 8 Drawing Sheets
